George W. Tremble for his
Attorney G. B. Towne

United States Patent Office.

GEORGE W. TRIMBLE, OF BLOOMSBURG, PENNSYLVANIA, ASSIGNOR TO
HIMSELF, E. HUGHES, AND WESLEY BUCKEL, OF SAME PLACE.

Letters Patent No. 75,608; dated March 17, 1868.

IMPROVEMENT IN MINER-LAMPS.

The Schedule referred to in these Letters Patent and making part of the same.

TO ALL WHOM IT MAY CONCERN:

Be it known that I, GEORGE W. TRIMBLE, of Bloomsburg, in the county of Columbia, and State of Pennsylvania, have invented a new and useful Improvement in Mining and Furnace-Lamps; and do hereby declare that the following is a full, clear, and exact description of the construction and operation of the same, reference being had to the accompanying drawings, making a part of this specification, in which—

Figure 1 is a side elevation.

Figures 2, 3, and 4 are views in detail of the feeding-device of the lamp.

The nature of my invention consists in providing the tube or spout of the lamp with a simple and novel device for feeding the wick to the flame, instead of pushing it out of the tube by striking the bottom of the lamp on something, which in a short time so injures the lamp as to cause it to leak, and where many are used, considerable expense is entailed for repairing, which I obviate by the device, as will hereinafter be shown.

To enable any one skilled in the art to make and use my invention, I will proceed to describe its construction and operation.

A is the lamp, B is the tube or spout, C is the wick. The device consists of an elongated piece of tin, *a*, tapering on both sides toward the end, where it is rounded. The other end is cut inwardly to the centre at a suitable angle, and thence cut inwardly again to a slot, *b*, which is to receive the flanges of the thumb-slide for fastening it thereto. This piece is then bent around, and assumes the form seen in figs. 1 and 2. An elongated slot is made in the tube, with small strips of tin soldered around the edges thereof, to give the proper stiffness, for the slide, which will work therein against the edges. A plate, D, having a corresponding slot, *c*, is placed over the strips and soldered on to the tube. E is the thumb-slide, provided with a guide-bar, *d*, which is inserted in an opening of the cross-piece *e*, soldered on to the plate at its lower end. The flanges, *g*, of the slide are inserted through the slots of the plate and tube, and thence through the device, where they are bent over in opposite directions, and made fast to the under sides of the device.

Operation: By working the thumb-slide up and down on the plate of the tube, the angular pointed ends or sides of the device, which almost entirely encompass the wick, shove it forward, and thus feed it to the flame.

Having thus fully described my invention, what I claim therein as new, and desire to secure by Letters Patent, is—

Providing the tube or spout of a mining and furnace-lamp with a feed-device for the wick, substantially as described.

GEORGE W. TRIMBLE.
